MEANS FOR SLITTING AND WINDING PAPER FROM PAPER MAKING MACHINES

Filed Aug. 8, 1924

FIG. 5.

FIG. 6.

FIG. 1.

FIG. 4.

FIG. 2. 16a 20a 23

FIG. 3.

Inventor
Philip D. Parsons.

By Attorney.

UNITED STATES PATENT OFFICE

PHILIP D. PARSONS, OF PHILADELPHIA, PENNSYLVANIA, ASSIGNOR TO SCOTT PAPER COMPANY, A CORPORATION OF PENNSYLVANIA

MEANS FOR SLITTING AND WINDING PAPER FROM PAPER-MAKING MACHINES

Application filed August 8, 1924. Serial No. 730,830.

Heretofore it has been the practice in paper making to wind the web leaving the last drying cylinder of a paper making machine into a single large roll upon a central core or cylinder having extended ends constituting journals, subsequently severing the paper web and starting it to wind upon a second core or cylinder, and at this time transferring the fully wound paper roll to a separate machine for 10 slitting and rewinding; and during the rewinding operation, trimming and slitting the web into desired widths of roll for subsequent treatment in making articles such as towels and napkins, for example; and further, during 15 the transfer and rewinding of the paper roll, separately transferring the new roll being wound with the paper from the drying cylinders to the journal supports formerly employed for the paper roll which is transferred to the trimming, slitting and rewinding machine, and thereafter repeating the operation.

Machines for carrying out the reeling operation for preparing the web into a single 25 roll are described in United States Letters Patent No. 1,248,542, dated December 4, 1917, and granted to C. E. Pope, and from this machine the paper roll has been transferred to a complicated independent machine for slitting and rewinding which I heretofore have constructed for trimming and dividing the single large roll into a plurality of rolls of the same diameter but of less length. The employment of this secondary trimming, slitting 30 and rewinding apparatus is costly and involves much additional labor and handling of the paper before the trimmed paper and plurality of smaller rolls are obtained.

The object of the present invention is to 40 provide means for enabling the paper web to be trimmed, slit and formed into rolls of the desired axial lengths, all as one operation upon the web as it leaves the last drying cylinder of the paper making machine, said 45 trimming and slitting taking place immediately before the act of winding the paper into roll form in the first instance, thereby entirely eliminating the use of the means for trimming, slitting and rewinding of the paper 50 rolls together with all of the labor and cost

incident thereto and heretofore required as part of the paper making system.

More particularly, my invention is an improvement upon the Pope winding reel set out in Letters Patent No. 1,248,542, aforesaid, or a machine of that type in connection with paper making, by providing the reel thereof with preliminary slitting cutters for trimming the margins of the paper web prior to winding; and where a plurality of separate 60 rolls are to be simultaneously formed, slitting the web accordingly, to provide the necessary narrower webs for making such rolls, it being further understood that where a plurality of such rolls are to be simultaneously formed, 65 the mandrel upon which they are wound is desirably provided with a corresponding plurality of tubes or cores clamped or held end to end to rotate as a unit for being frictionally driven in following the general practice of 70 the Pope reel equipment.

With these and other objects in view, my invention consists of means for carrying them into practice as more fully set out hereinafter and defined in the claims.

Referring to the drawings: Fig. 1 is a side elevation of apparatus embodying my invention; Fig. 2 is a plan view of the same; Fig. 3 is a plan view of one of the receiving cylinders for the paper roll when being wound; Fig. 4 is an end view of one of the clamping collars; Fig. 5 is a vertical sectional view showing the winding cylinder, mandrel and slitting cutters; and Fig. 6 is a side view of a modification of the slitting means.

Referring more particularly to the details of the apparatus embodying my invention, as shown in Figs. 1, 2, 3 and 4, A is the last of the drying cylinders of the paper making machine or other equivalent apparatus. B 90 is the guide about which the paper P passes on its way to the slitters and winding means embodying my improvements. 2 is the body or main frame of the winding means and is provided with bearings 4 in which is journaled the winding drum 3 which may be driven by a belt wheel or by other suitable power. Arranged upon the bed frame and at a point adjacent to the upper part of the drum 3 and between it and the guide B, are 95 100

journalized the slitting cylinder and disk cutters which may be of any suitable construction. As shown, they comprise a cylinder 7^a and a shaft 7^b having the slitting cutters 5 7 in disk form. The cylinder 7^a and the shaft 7^b of the cutters are geared together at 8 so that they revolve at the same surface speeds and act upon the paper web passing between them. Immediately in front of the 10 slitting cutters is a guide 5 between which and the guide B there may be longitudinal guide bars 6 forming a grating against which the paper web travels and by which it is guided to the slitting cutters. The cylinder 15 7^a and cutter shaft 7^b are geared together by the gearing 8. The gearing 8 is geared by an intermediate gear 9 with a gear 10 on the shaft of the drum 3, the transmitting connection thus made between the drum and the 20 slitting means insuring the surface speeds of the slitting cutters and the drum to be the same. At each end of the drum 3 is a frame 16 having a pivotal axis at 17 above the journal 4 of the drum and the upper end of 25 each of these frames is formed with a fork or jaw 15 in which a box 14 may detachably fit, said boxes providing bearings for the shaft 13 of the winding tubes 12^a and 12^b, as more fully illustrated in Fig. 3. In this 30 construction, the box bearings 14 are adjustable radially in the forked portion of the frame 16 whereby such boxes in connection with the tube shaft 13 may be inserted or removed in the frame 16 as carriers and which 35 also permits automatic adjustment radially when the tubes are being wound with paper. These frames 16 are provided with segmental curved racks 16^a whose curvature is formed about the pivotal connection 17 as a center, 40 and said segmental racks are engaged by pinions 19 on a transverse shaft 20 having a hand wheel 20^a and by means of which the frames 16 may be rocked about their pivotal points 17 for moving the shaft 13 and the 45 winding tubes thereon backward over the winding drum, and for effecting the transfer of the boxes 14 together with the shaft 13 and the tubes thereon into custody of the radial arms 21. The radial arms 21 are secured to a transverse shaft 21^a having a hand 50 wheel 23 by which it may be adjusted when desired. The shaft 21^a is journalized in the main frame at 21^b, arranged to the rear of the drum 3 and also to the rear of the shaft 55 20 so that the free ends of the radial arms 21 may swing toward or from the upper portion of the drum 3. The upper ends of these arms 21 are formed with forked bearings 22 which are so shaped as to be adapted 60 to receive the shaft 13, just inside of the boxes 14, when transferred from the frame 16 to the radial arms 21.

It will be understood that when the parts are in the position shown in Fig. 1, the paper web P is being wound upon the cylinder 12

composed of the tubes 12^a and 12^b, the periphery of the paper roll H being formed thereon resting in frictional contact with the surface of the drum 3 and whose rotation causes the paper roll to be rotated to a gradually increasing diameter and until it has reached its maximum size. During this operation, the supporting arms 21 also swing backward due to the increasing diameter of the paper roll. While this operation is going on, the 70 frames 16 may be moved back to their original positions shown in Fig. 1 by means of the racks and pinions before referred to, the same being operated by means of the hand wheel 20^a. At this time there is no cylinder 75 12 and its shaft journalized in bearings in the upper part of the frame 16, but such cylinder is required to be lifted into place as shown in Fig. 1 just before the completion of the paper roll H, so that when the paper 80 web adjacent to the paper roll is required to be severed, the free end of the paper web thus provided must be pressed over the cylinder 12 to attach itself to said cylinder as a core and by which the next operation for 85 making the paper roll is started. The severing of the paper web between the paper roll H and the receiving cylinder 12 may be effected by a blast of air under the paper web or by any other suitable means which will 90 sever the web. Ordinarily, the paper may be separated by the air blast just as is explained in United States Letters Patent No. 1,248,542 of December 4, 1917, aforesaid.

It will be understood that during the reeling or winding operation of the paper about the cylinder 12 to constitute the paper roll H, that the paper web passing from the dryer A and over the guiding means B and 6 is slit at the middle and also adjacent to the edges 100 of the paper web, whereby the web is trimmed and at the time split longitudinally so that when the strips are wound they will form rolls upon separate core tubes 12^a and 12^b, the said trimming and slitting being accomplished 105 preliminary to the winding of the paper on the tubes, and in this manner obviating wholly the subsequent transfer of the untrimmed and unslit paper roll to the special slitting and rewinding machines heretofore employed.

When the paper roll H is of the proper diameter, a suitable lift (not shown) engages the ends of the shaft 13 and lifts the roll from the radial arms 21 and removes it to any place desired. The arms 21 are, thereafter adjusted forward toward the revolving drum 3 and are once more in position for receiving the new cylinder 12 which is journalized in the forked ends 15 of the frames 16. Before the 110 transference of the new cylinder, it is manifest that paper will be winding upon it, and the operation which takes place with the new cylinder is the same as takes place with the former cylinder of the roll H, but the main 115 120 125 130

winding is always performed while the cylinder is in the custody of the arms 21.

It will be understood that the operation is a continuous one, that is to say, the paper web P is continually travelling toward the reeling means and being slit and trimmed on its way to said means, said means also acting to draw the paper forward from the drying cylinder A and avoid any looseness therein. This is accomplished by making the surface speed of the drum 3 equal to or very slightly greater than the speed of the paper web leaving the drying cylinders. Where the speed of the drum is slightly in excess, there is a frictional tendency to stretch the paper as it is being wound upon the cylinders 12 and in that manner insure a tight roll being formed.

The construction of the winding cylinder 20 and its connecting parts is best shown in Fig. 3, from which it will be seen that the shaft 13 is provided at each end of the box 14 in which it is journaled and by which it is supported in the forked ends 15 of the radial frames 25 16. The shaft is provided with collars 13^a by which the position of the boxes are assured and these boxes may, if desired, be of a size which will permit of them being drawn through the tubes 12^a and 12^b forming the cylinder 12, though, if desired, said boxes 30 may be removable from the shaft 13 when it is desired to separate the rolls of paper each associated with its respective tubular core 12^a and 12^b. It will be further seen that the shaft 35 13 is provided with plug portions 24 and 25 over and upon which the tubular parts 12^a and 12^b are arranged and supported, the plug 25 being longer than the plugs 24 as it supports the abutting ends of the two tubular 40 core portions 12^a and 12^b. Near one end of the shaft and adjacent to one of the plugs 24 is a collar 26 secured to the shaft 13 and at the other end and between the plug 24 and the bearing block 14, there is arranged a second collar 27 and a locking nut 28 screwed upon the shaft. The collar 27 may be slotted, as at 27^a, Fig. 4, and may be slipped over the shaft 23 before being clamped against the end 45 of the tubular core 12^a, by the nut 28. When 50 this is being done, tube 12^b is clamped against the collar 26 while tube 12^a is tightly abutted at 12^c against the end of the tube 12^b and at the same time the collar 27 and nut 28 are the clamping means for the outer end of the tube 55 12^a. When the paper webs are wound upon these tubes 12^a and 12^b, they should be separated from the shaft 13 and its plugs, but with the respective tubes 12^a and 12^b remaining in the rolls as cores thereafter and by which 60 they may be supported in other machines where they may be subjected to further treatment. To accomplish this, the nut 28 is loosened, the collar 27 is withdrawn and the shaft together with collar 26 and its plugs 24 and 65 25 and nut 28 and with or without its bearing

14, are withdrawn through the tubes 12^a and 12^b. When this is done, the tubes will be entirely separated and it will have its own tubular core. New tubes are then assembled on the shaft 13 to reform the cylinder 12 and when thus formed it is once more in condition for utilization in the machine as before described.

I have described my improvements as applied in connection with a type of winding device set out in Letters Patent No. 1,248,542, aforesaid, but I do not restrict myself to the use of my improvements in connection with that particular type of machine, as my invention comprehends the combination of the drying cylinders of a paper making machine or its equivalent, a reeling mechanism to receive the paper as rapidly as delivered and an intermediate means for trimming and slitting the paper web after its delivery from the drying cylinders and before it reaches the winding or reeling means; and in the preferred form of my apparatus, the said reeling means embodies a winding cylinder composed of a plurality of core tubes which, when assembled, constitute a single cylinder but which subsequently may be separated so that part remains with one paper roll and part with another to constitute tubular cores thereof.

In place of driving the slitting cutters 7 and roll 7^a by gearing as in Figs. 1 and 5, the roll 7^a may be driven from the drum 3 by a belt 9^a and the slitting cutters 7 may be loosely carried on a rod 7^b held in pivoted arms 7^c drawn down by springs 7^d to insure the necessary friction of the cutters on the roller, all as shown in Fig. 6. When inserting the paper the arms and cutters may be moved away from the roller.

By the employment of the improvements herein set out, there is very great saving in apparatus required, in the space occupied, in replacements and repairs, and in the number of operatives necessary for the production of a given number of rolls of paper in complete form with cores attached, as compared to what has heretofore been the practice.

In this application no claim is made to the method of simultaneously preparing duplicate rolls of paper as herein set out and practiced with the use of the apparatus forming the subject matter of the present application, and neither do I claim herein the specific construction of the revolving drum upon which the plurality of rolls of paper are simultaneously wound, as these subject matters are basis of other applications.

I have described my improved means in that particularity which I deem to be the best exposition of my invention, and that which I prefer in commercial practice, but I do not restrict or confine myself to the minor or secondary details, as such are susceptible of modification which may be resorted to as mat-

ters of mechanical skill and without a departure from the spirit of the invention.

Having now described my invention, what I claim as new and desire to secure by Letters Patent is:

- 5 1. In a paper slitting and winding machine, the combination of guiding means over which the paper web is conveyed, with slitting mechanism for dividing the paper web 10 into a plurality of narrower webs, a rotating drum over and in contact with which the plurality of narrower webs are caused to simultaneously travel, a multiple core rotatable member upon the several cores of which the 15 plurality of narrower webs are respectively wound and in which the subdivision of the core is in alinement with the slitting mechanism whereby the two adjacent edges of the slit web will be received respectively upon 20 the adjacent ends of the multiple core, means for temporarily supporting the rotatable member whereby it may move away from the drum while maintaining the paper rolls upon it in contact with said drum and whereby 25 friction is provided for rotating the member together with the paper rolls thereon, a second rotatable multiple core member arranged intermediate of the first mentioned 30 rotatable multiple core member and the slitting devices, means for supporting the second rotatable multiple core member in rolling contact with the drum and the paper travelling thereon with freedom of movement toward or from said drum whereby the paper 35 web between the first and second rotatable members may be ruptured upon completion of the rolls upon the first rotatable member and the ruptured web wrapped about the second rotatable member for starting a second 40 plurality of rolls, and means for moving the support for the second rotatable member circumferentially about the drum for transferring it to the supporting means which temporarily support the first rotatable member.
- 45 2. In a paper slitting and winding machine, the combination of guiding means over which the paper web is conveyed, with winding mechanism for winding the paper web in roll form, and slitting mechanism for dividing the paper web into a plurality of narrower webs 50 arranged between the guiding means and the winding means, and wherein further the winding means comprises a revolving drum, a transverse shaft having a 55 plurality of tubular parts clamped thereon in end to end abutted relation and forming tubular cores for the respective rolls of paper formed from the plurality of webs after leaving the slitting devices and in which the abutting 60 ends of the tubular cores are in alinement with the slitting devices whereby the two adjacent edges of the slit web will be received respectively upon the adjacent ends of the abutting tubular cores, and means for supporting the shaft and the tubular parts par-

allel to the rotating drum and permitting adjustment relatively to the same as the rolls increase in diameter by being frictionally driven by the drum.

3. In a paper slitting and winding machine, 70 the combination of guiding means over which the paper web is conveyed, with winding mechanism for winding the paper web in roll form, and slitting devices for dividing the paper web into a plurality of narrower webs 75 arranged between the guiding means and the winding means, said slitting devices comprising three pairs of slitting cutters, two pairs of which are arranged far apart to trim the lateral edges of the paper web and an intermediate pair provided for slitting the web into two narrower web portions, and wherein further, the said winding mechanism comprises a revolving drum, a transverse shaft 80 having thereon a plurality of tubular parts arranged end to end in abutting alinement axially and with the intermediate pair of slitting cutters whereby the two adjacent edges of the slit web formed by said intermediate pair of slitting cutters will be received respectively upon the adjacent ends of the abutting tubular cores upon which the respective webs of paper are wound, said tubular cores being detachable with respect to each 85 other and to the transverse shaft whereby the 90 rolls of paper may be separated and each with its individual core, and in which means are also provided for supporting the transverse shaft whereby the paper rolls being formed thereon may be maintained in frictional contact with the revolving drum during their 95 formation.

4. In a paper slitting and winding machine, 100 the combination of guiding means over which the paper web is conveyed, with winding mechanism for winding the paper web in roll form, and slitting mechanism for dividing the paper web into a plurality of narrower webs 105 arranged between the guiding means and the winding means, and wherein further, the slitting devices comprise a plurality of pairs of slitting cutters, two pairs arranged far apart to trim the lateral edges of the paper web and intermediate cutters for slitting the web into a plurality of narrower web portions, and wherein further, the winding means comprises a revolving drum, a transverse shaft having thereon a plurality of tubular parts arranged in alinement and constituting cores 110 upon which the respective webs of paper are 115 wound and in which the abutting ends of the tubular cores are in alinement with the intermediate slitting cutters whereby the two adjacent edges of the slit web will be received respectively upon the adjacent ends of the abutting tubular cores, said tubular cores being 120 detachable with respect to the transverse shaft whereby the rolls of paper may be separated and each with its individual core, and means 125 for supporting the transverse shaft whereby 130

the paper rolls being formed thereon may be maintained in frictional contact with the revolving drum during their formation, and in which further, there is provided separate supporting means for a duplicate shaft with tubular core parts intermediate of the slitting devices and the means for supporting the shaft upon which the paper rolls are being wound, said separate supporting means adjustable for transferring the shaft it supports into the custody of the supporting means for the shaft upon which the paper roll is being wound as soon as the paper rolls thereof are fully wound and removed whereby the machine may be continuous in its winding operations.

5. In a paper slitting and winding machine, the combination of guiding means over which the paper web is conveyed, combined with a revolving drum in contact with the surface of which the paper web is guided, two transverse shafts and separate supports therefor upon which the paper web is wound successively in forming consecutive rolls, means for guiding one of the shafts radially with respect to the drum to compensate for the gradually increasing diameter of the paper roll, means for adjusting the other of the shafts circumferentially about the drum for transferring its shaft to the supports first mentioned, a plurality of tubular core parts surrounding each of the shafts and in end to end alinement thereon, and means intermediate of the drum and the guiding means for slitting the paper web into a plurality of narrower webs immediately prior to their being wound upon the tubular core parts carried by the respective transverse shafts and in which the subdivision of the core parts in their end to end alinement is in alinement with the slitting means for the paper web whereby the two adjacent edges of the slit web will be received respectively upon the adjacent ends of the core parts, whereby when the rolls are fully wound the withdrawal of the transverse shaft will provide a plurality of independent rolls each having a tubular core.

In testimony of which invention, I have hereunto set my hand.

50 PHILIP D. PARSONS.
